US0D1021040S

(12) **United States Design Patent** (10) **Patent No.:** **US D1,021,040 S**
(45) **Date of Patent:** **** Apr. 2, 2024**

(54) **FILTER**

(71) Applicant: **RZ Industries LLC**, Burnsville, MN (US)

(72) Inventor: **Steve Gordon Torbenson**, Lakeville, MN (US)

(73) Assignee: **RZ Industries LLC**, Burnsville, MN (US)

(**) Term: **15 Years**

(21) Appl. No.: **29/810,585**

(22) Filed: **Oct. 6, 2021**

(51) LOC (14) Cl. **23-04**

(52) U.S. Cl.

USPC **D23/365**

(57) **CLAIM**

The ornamental design for a filter, as shown and described.

DESCRIPTION

FIG. 1 is a front lower left perspective view of a filter, showing the present design;

FIG. 2 is a front lower right perspective view of the filter in FIG. 1;

FIG. 3 is a front upper left perspective view of the filter in FIG. 1;

FIG. 4 is a front upper right perspective view of the filter in FIG. 1;

FIG. 5 is a rear lower left perspective view of a filter, showing the present design;

FIG. 6 is a rear lower right perspective view of the filter in FIG. 1;

FIG. 7 is a rear upper left perspective view of the filter in FIG. 1;

FIG. 8 is a rear upper right perspective view of the filter in FIG. 1;

FIG. 9 is a front view of the filter in FIG. 1;

FIG. 10 is a left side view of the filter in FIG. 1;

FIG. 11 is a right side view of the filter in FIG. 1;

FIG. 12 is a top view of the filter in FIG. 1;

FIG. 13 is a bottom view of the filter in FIG. 1; and,

FIG. 14 is a rear view of the filter in FIG. 1.
